HAIR STYLING TOOL

Hector S. Cournoyer, Miami Beach, Fla., assignor to Grooming Developers, Inc., Chicago, Ill., a corporation of Illinois

Filed Oct. 3, 1966, Ser. No. 4,154

Term of patent 14 years

(Cl. D86—8)

FIG. 1 is a side perspective view of a hair styling tool showing my new design;

FIG. 2 is a side elevational view thereof;

FIG. 3 is a bottom plan view thereof looking from line 3—3 of FIG. 2;

FIG. 4 is an enlarged sectional view taken on line 4—4 of FIG. 2; and

FIG. 5 is an enlarged sectional view taken on line 5—5 of FIG. 2.

The essential features of my design reside in the full line disclosure on the drawing.

I claim:

The ornamental design for a hair styling tool, as shown and described.
